(57) **CLAIM**

The ornamental design for a USB device, as shown and described.

DESCRIPTION

FIG. 1 is a front perspective view of a USB device showing our new design;

FIG. 2 is a rear perspective view thereof;

FIG. 3 is another front perspective view thereof;

FIG. 4 is another rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The shade lines in the Figures show contour and not surface ornamentation.
